(57) **CLAIM**

The ornamental design for a blow dry brush, as shown and described.

DESCRIPTION

FIG. 1 is a front perspective view of a blow dry brush embodying our new design;

FIG. 2 is a rear perspective view of FIG. 1;

FIG. 3 is a left-side elevation view of FIG. 1;

FIG. 4 is a right-side elevation view of FIG. 1;

FIG. 5 is a front elevation view of FIG. 1;

FIG. 6 is a rear elevation view of FIG. 1;

FIG. 7 is a top plan view of FIG. 1; and,

FIG. 8 is a bottom plan view of FIG. 1.

The broken lines illustrate portions of the blow dry brush that form no part of the claimed design.

Color and texture may or may not form part of the claimed design without departing from the design disclosed. The inventors anticipate that the invention can be any part, portion, element, or combination of elements of the depicted design. The addition of further physical elements such as ribs, ridges, textures, and/or dimples are not excluded. Any part, portion, element, or combination of elements of the depicted design which is novel may represent an invention or design for which protection is or may be claimed in the future.
